US00D604729S

(12) **United States Design Patent**
Andre et al.

(10) **Patent No.:** **US D604,729 S**
(45) **Date of Patent:** ** *Nov. 24, 2009

(54) **ELECTRONIC DEVICE**

(75) Inventors: **Bartley K. Andre**, Menlo Park, CA (US); **Daniel J. Coster**, San Francisco, CA (US); **Daniele De Iuliis**, San Francisco, CA (US); **Evans Hankey**, San Francisco, CA (US); **Richard P. Howarth**, San Francisco, CA (US); **Jonathan P. Ive**, San Francisco, CA (US); **Duncan Robert Kerr**, San Francisco, CA (US); **Shin Nishibori**, Portola Valley, CA (US); **Matthew Dean Rohrbach**, San Francisco, CA (US); **Peter Russell-Clarke**, San Francisco, CA (US); **Douglas B. Satzger**, Menlo Park, CA (US); **Christopher J. Stringer**, Woodside, CA (US); **Eugene Antony Whang**, San Francisco, CA (US); **Rico Zorkendorfer**, San Francisco, CA (US)

(73) Assignee: **Apple Inc.**, Cupertino, CA (US)

(**) Term: **14 Years**

(21) Appl. No.: **29/294,332**

(22) Filed: **Jan. 4, 2008**

(51) LOC (9) Cl. **14-02**

(52) U.S. Cl. **D14/314**

(58) **Field of Classification Search** D14/314, D14/348, 363-369, 353-356; D13/162, D13/184, 199; 312/223.1-223.3; 360/99.01-99.12; 369/34.01, 36.01; 361/680-686, 690-696

(57) **CLAIM**

The ornamental design for an electronic device, as shown and described.

DESCRIPTION

FIG. 1 is a front, top perspective view of an electronic device showing our new design;

FIG. 2 is rear, bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines are environmental and form no part of the claimed design.

1 Claim, 5 Drawing Sheets
